[57] CLAIM

The ornamental design for a tricycle having a passenger carrier, as shown and described.

DESCRIPTION

FIG. 1 is a perspective view of the front and one side of a tricycle having a passenger carrier showing my new design;

FIG. 2 is a side elevation view thereof, it being understood that the opposite side is substantially a mirror image of that shown;

FIG. 3 is a top plan view thereof; and,

FIG. 4 is an enlarged rear perspective view thereof.

FIG. I.

FIG. 2

FIG. 3

FIG. 4
